UNITED STATES PATENT OFFICE.

JOSEPH LEWIS FREDLIHP, OF MADERA, CALIFORNIA.

BELT-LOOP.

980,175.

Specification of Letters Patent. Patented Dec. 27, 1910.

Application filed August 30, 1909. Serial No. 515,251.

To all whom it may concern:

Be it known that I, JOSEPH L. FREDLIHP, a citizen of the United States, residing at Madera, in the county of Madera and State 5 of California, have invented a new and useful Belt-Loop, of which the following is a specification.

This invention relates to belt loops and its object is to provide a simple, durable and 10 inexpensive device of this character particularly designed for holding belts upon the waist-bands of trousers, and the device is also of considerable convenience for engaging the button-hole portions of suspenders.

15 Another object is to provide a device of this character which can be readily applied to a garment and which will not detract from the appearance thereof.

With these and other objects in view, the 20 invention consists in certain novel details of construction and combinations of parts hereinafter more fully described and pointed out in the claim.

In the accompanying drawings, the preferred forms of the invention have been 25 shown.

In said drawings:—Figure 1 is a view showing a garment in dotted lines the fasteners thereon being indicated in full lines. 30 Fig. 2 is a detail view of one of the fasteners. Fig. 3 is a similar view of another form of fastener. Fig. 4 is a perspective view of a third form of fastener.

Referring to the figures by characters of 35 reference, 1 designates an elongated, flat, metallic strip provided at each end with a hooked portion, said portions being indicated by the numerals 2 and 3 respectively. As indicated in the drawings the crown portion 40 of each of these hooks is bowed transversely so that its inner face will be convex from side to side, and thus reduce to the minimum wear upon the object engaged by the hooked portion. In one form of the device, 45 one of the ends of the said strip 1 is extended from the hooked portion 2 in the form of an elongated tongue 4 while the other end portion thereof is also extended into a shorter tongue 5 designed to lap and 50 normally bear upon the terminal portion of the tongue 4. This tongue 5 may be provided with a transverse outstanding bead as shown at 6 and which forms an inner depression. As shown in Fig. 2, the free end 55 of tongue 4 preferably extends partly across this depression. A suitable number of aper-

tures 7 may be formed within the strip 1 for reception of a thread or other means utilized for fastening the device upon a garment. If preferred, and as shown in Fig. 3, the elongated strip may be provided with tongues 8 extended toward each other and each of which is provided with an enlargement or head 10 preferably substantially circular in form. In both forms of garment supporter 60 the distance between the strip 1 and the tongues is approximately equal to the thickness of a belt within the hooked ends of the supporter, and the distance between the bends is equal to the width of said belt. 65

In using the device shown in Figs. 1 and 2, the strips 1 are sewed or otherwise fastened to the waist band of the trousers and the belt is then inserted endwise between the strips and the tongues 4 and 5 so as to fit 70 snugly within the device. The button-hole or eye portions of suspenders are then placed in engagement with the tongues 5 by slipping them between the lapping portions of the tongues 4 and 5 and then positioning the 75 lower ends of said button-hole portions between the belt and the waist band of the trousers. It is apparent therefore that the supporters such as shown in Figs. 1 and 2 not only constitute efficient means for holding the belt securely upon the garment but they also take the place of buttons which are ordinarily used for engagement with suspenders. The form of device shown in Fig. 80 3 is designed to be used and applied in the 85 same manner as is the device shown in Figs. 1 and 2.

When it is desired to remove the button-hole portion or eye of suspenders from engagement with the loop shown in these Figs. 95 1 and 2, the said portion is shifted downwardly until it is seated within the inner depression formed by bead 6 and upon the outer face of the projecting end of tongue 4. By then continuing to pull downward on the 100 eye of the suspenders, it will wedge between said projecting end of tongue 4 and the free end of the tongue 5 and will thus force the two tongues apart and pass out of the loop.

Another form of garment supporter has 105 been indicated in Fig. 4, this supporter consisting of an elongated strip 11 having hooked portions adjacent the ends thereof such as indicated at 12, there being tongues 13 extending from the hooked portions and 110 each provided with a disk like head 14. Apertures 15 are formed within these heads and

are designed to receive threads for the purpose of fastening a supporter upon a garment.

In the form of device shown in Fig. 4 the 5 distance between the head 4 and the strip 1 is substantially equal to the thickness of a belt which is to be held in place and after the heads 14 have been fastened to the waist-band of a garment by sewing them thereto 10 or by securing them in any other preferred manner, the belt is inserted endwise through the supporter. In this form of device it is of course necessary to apply the button hole 15 portions of suspenders before the supporter is fastened to the waist band.

It is to be understood that various changes 20 may be made in the construction and arrangement of parts without departing from the spirit or sacrificing the advantages of the invention. A metal garment supporter herein described is designed to be used in lieu of the ordinary fabric strap attached to the waist-band of trousers and is much more desirable in view of the fact that it not only 25 serves to hold a belt in proper position but it also engages the button hole portion of suspenders and dispenses with the use of buttons for the same purpose. Moreover, if pre-

ferred, the supporter herein described can be fastened to the inner face of a waist band 30 as for example, when it is desired to attach an electric belt to the garment.

What is claimed is:—

As an article of manufacture a belt loop 35 consisting of a resilient strip of material having opposed hook portions, a straight tongue extending from one of said portions and parallel with the intermediate portion of the strips, and another tongue extending from the other hooked portion and contacting at its end upon the outer face of the first mentioned tongue, there being a transversely 40 extending depression in the inner face of said lapping tongue, the straight tongue being extended a short distance across the depression and both of said tongues being 45 adapted to rest flat upon a belt within the loop.

In testimony that I claim the foregoing as my own, I have hereto affixed my signature in the presence of two witnesses.

JOSEPH LEWIS FREDLIHP.
